UNITED STATES PATENT OFFICE.

VERNON HOXIE, OF ADRIAN, MICHIGAN, ASSIGNOR TO LAMB WIRE FENCE COMPANY, OF ADRIAN, MICHIGAN, A CORPORATION OF MICHIGAN.

WIRE FEED, STRAIGHTENING, AND CUTTING MECHANISM.

No. 804,321.

Specification of Letters Patent.

Patented Nov. 14, 1905.

Application filed February 20, 1904. Serial No. 194,480.

To all whom it may concern:

Be it known that I, VERNON HOXIE, a citizen of the United States, and a resident of Adrian, in the county of Lenawee and State of Michigan, have invented certain new and useful Improvements in Wire Feed, Straightening, and Cutting Mechanism; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to wire-working machinery, and has particular reference to mechanism for feeding and straightening the wire, cutting the same into predetermined lengths, and intermittently delivering these cut sections into the connected machine to be formed thereby into wire fabric or other articles.

The primary object of my invention is to provide simple and efficient mechanism whereby the feed of the wire to the straightening-arbor is automatically stopped at regularly-timed intervals to permit of a partial rotation of the receiving-shaft for the purpose of intermittently cutting the wire being fed and delivering a cut section thereof into the forming-machine, thus preventing the buckling or burning off of the wire that is incident to machines of this class in which a continuous feed is employed.

Further objects of the invention are the provision of improved means for cutting the wire into sections and improving upon and simplifying the construction and arrangement of the mechanism for controlling and properly timing the operation of the associated parts.

The invention is fully described in the following specification, of which the accompanying drawings form a part, in which—

Figure 1 is a plan view of the mechanism comprising the invention, showing the shafts broken in two and the cutting parts partly in section. Fig. 2 is a cross-sectional view of the wire-receiving shaft and associated cutting parts, taken on the dotted line xx in Fig. 1. Fig. 3 is a side elevation of a portion of the parts shown in Fig. 1, with clutch mechanism shown partly in vertical section. Fig. 4 is an end elevation showing the wire-feed mech-

anism. Fig. 5 is a cross-sectional view of the clutch mechanism, taken on the dotted line yy in Fig. 3; and Fig. 6 is a side elevation of the feed-chair and supported mechanism for feeding the wire into the machine.

Referring to the drawings, A represents a portion of the frame employed for supporting the parts of my invention in operative position and has provided thereon the bearing-blocks A' and A'' , which are adapted to receive the ends of and support the straightening-arbor B in elevated position, the said arbor B having a belt-pulley b provided at one end, by which it may be rapidly revolved from a driving-shaft (not shown) or in any suitable manner. No claim is made on the arbor B, as any suitable design of straightener may be used.

Mounted in substantial longitudinal alignment with the arbor B is the wire-receiving shaft C, which has one of its ends journaled in the bearing-block A' and its other end journaled in a suitable bearing provided in the supporting-standard D, arising from the frame, the latter end of said shaft being extended beyond said standard D and having the large spur-gear E keyed thereon. The shaft C is provided on its periphery with a multiplicity of radially-disposed longitudinal grooves or wire-receiving sockets c , (shown in the drawings as eight in number,) which extend the entire length of said shaft and are adapted to longitudinally align with the central opening b' through the arbor B and plug B' by reason of the adjacent end of the shaft C being journaled in the bearing-block A' in slightly offset position from said arbor, thus enabling the wire a as it is fed into the machine to pass continuously through the arbor B, bearing-block A' , and alining groove c in the shaft C until its advance is stopped by means herein-after described.

The cap for retaining the shaft C in the bearing provided in the standard D for its reception is provided with the arms d and d' , the former projecting horizontally around the spur-gear E and having the lever-arm e pivoted thereto and the latter projecting inwardly over the shaft C and having one end of the plate f secured thereto, the said plate having its other end secured to the block A' and being adapted to at all times cover the groove c , alining with the opening b' through the plug B', and prevent the buckling of the wire a as it is being passed therein.

The lever *e* is horizontally disposed in diametric relation to the outer side of the gear *E* and has the sleeve *e'* provided centrally thereon to receive the rotatable trip-wire-carrying member *F*, the said member being provided with a peripheral recess (shown by dotted lines in Fig. 1) for receiving the retaining-pins *e''*, carried by said sleeve and adapted to normally abut against the hub of the gear *E*. The trip-wires *f'*, which pass through apertures provided in the member *F* and are adjustably secured therein by any suitable means, (not shown,) correspond in number to the grooves *c* in the shaft *C* and are adapted to have their inner ends loosely extended through the hub of the gear *E* within said grooves to a point therein where it is desired to stop the feed of the wire *a*, the same being accomplished by the end of the advancing wire *a* engaging the alining trip-wire *f'* and forcing the member *F* and connected lever *e* outward for the purpose of throwing mechanism hereinafter described into operation.

Arising laterally from the frame portions *A* and *D* are the supporting-standards *G* and *G'*, which are provided in their upper ends with suitable bearings in which is mounted the horizontal shaft *H*, the same being shown as elevated slightly above the horizontal plane of the arbor *B* and shaft *C*. Mounted loosely on the shaft *H* in adjacent position to the support *G'* are the belt-pulley *I*, by which it may be rapidly revolved from a driving-shaft, (not shown,) and the connected sleeve *I'*, the latter being keyed or otherwise rigidly secured to said pulley, as shown in Fig. 3. In order to impart an intermittent rotation to the shaft *H* from the driven pulley *I*, I provide the sleeve *J*, which is rigidly keyed to said shaft in close abutting position to the hub of said pulley and carries the longitudinally-movable clutch-pin *j* therein, the said pin being adapted when released to engage a clutch-socket *i*, provided in the hub of said pulley, and impart rotation to said shaft. A substantially L-shaped lever *K* is fulcrumed to a boss projecting from the bracket *k*, secured to the frame portion *A*, and has its horizontally-disposed arm normally resting against the under side of the sleeve *J* within the peripheral recess or groove *J'* provided therein, and is also adapted to normally retain the clutch-pin *j* out of engagement with the pulley *I* by reason of said arm resting in a transverse notch provided therein. Expansion-springs *j'* and *K'* are shown in Figs. 3 and 5 for causing the pin *j* and lever *K*, respectively, to be held in proper positions. Movement is imparted to the lever *K* by means of the bell-crank lever *L*, which is fulcrumed to the boss *l*, projecting from the bracket *k*, and is adapted when rocked to release the lever *K* from the pin *j* and permit said pin to be forced into engagement with the pulley *I*.

The end of the shaft *H* is shown as projecting beyond the bearing-standard *G* and has

rigidly mounted thereon the cam disk or wheel *m* and the small gear *n*, the latter being adapted to mesh with the large gear *E* and cause a partial rotation of the shaft *C* when the clutch mechanism is thrown into operation. While I have shown and described a particular form of clutch mechanism for controlling the movements of the shaft *H*, I do not wish to confine myself to the use of such mechanism, as any suitably form may be used.

The lever *e*, which has its free end extended transversely of the end of the shaft *H* in adjacent position thereto, has the roller *m'* mounted thereon in proper position for engaging the cam-surface of the disk *m*, thus adapting a rotation of said disk to cause a return of said lever *e* and trip-wire-carrying member *F* to their normal positions (shown in Figs. 1 and 3) after they have been thrown outward by the feed-wire *a* engaging the alining trip-wire *f'*. A wire *o* or other suitable means connects the end of the lever *e* with one of the arms of the bell-crank lever *L*, thus causing an outward movement of the lever *e* to release the lever *K* from engagement with the clutch-pin *j*, which is then forced into engagement with the driven pulley *I* and causes a rotation of the shaft *H*. By the time the shaft *H* has completed a single revolution the lever *e* has been forced back to its normal position by the cam *m* and the clutch mechanism released from engagement with the pulley *K*.

A feed-roll chair *P* is formed or otherwise suitably secured to the outer side of the frame *A* and has journaled in its upper portions the transverse counter-shaft *p*, which has the feed-roll *p'* keyed to its central portion and the bevel-gear *q* keyed to one of its ends, the said gear being adapted to mesh with and be continuously driven by the companion bevel-gear *q'*, secured to and rotated by the sleeve *I'*, as shown in Figs. 1, 4, and 6. Elongated slots *r* are provided in the sides of the chair *P* in vertical alinement with the shaft *p* and have portions of the shaft-supporting member *Q* reciprocally mounted therein, the said portions being provided with bearings in which is mounted the transverse shaft *s*, which has the feed-roll *s'* centrally keyed thereon in vertical alinement and adapted to be rotated by frictional engagement with the constantly-rotating feed-roll *p'*. The feed-roll *s'* is caused to be intermittently lowered from engagement with the driven roll *p'* by means of the lever *T*, which is fulcrumed to a stud *t*, projecting horizontally from the end of the frame portion *A* below the chair *P*, and has the horizontally-disposed arm *T'* extending from its lower end and resting in the aperture *u*, provided in the lower portion of the member *Q*, and its upper end bifurcated to enable the friction-roll *t'* to be mounted therein. The friction-roll *t'* is adapted to bear against the periphery of the cam-disk *R*, which is keyed to the adjacent end of the shaft *H*, and nor-

1 mally seat in the slightly-indented portion R' thereon when said disk is at rest, thus causing the lever T to be intermittently oscillated and the feed-roll s' lowered from engagement 5 with the companion roll p' during a movement of the shaft H and disk R, as hereinafter described. In order to cause the shaft H and rigidly-connected parts to cease rotating as soon as the clutch mechanism has been released from the driven pulley I, I provide the 10 shoe U, which is retained in frictional engagement with the periphery of the cam-disk R by means of the supporting-bracket W, which projects outwardly from the standard G' and is properly adjusted by means of the set-screw w. The member Q is normally retained in elevated position by means of the bow-spring Q', which has its ends resting in the lower 15 portions of the slots r and its central portion bearing upwardly against a portion of said member. Set-screws are provided in the lower portions of the chair P and member Q for adjusting the spring Q' and lever T, respectively.

The mechanism for severing the wire a into 25 sections as it is passed into the machine consists of the hardened sleeve C', which is rigidly secured over a reduced portion of the shaft C in close abutting position to the bearing-box A', and the highly-tempered plug B', 30 which is provided with a longitudinal aperture therethrough and adapted to be inserted within a retaining-socket provided in said bearing-box A', with said aperture in longitudinal alignment with the aperture b' through 35 the arbor B, as shown in Figs. 1 and 2. The periphery of the sleeve C' is provided with a series of radially-disposed longitudinal wire-receiving grooves corresponding to the grooves c in the shaft C, of which it is a part, 40 as will be seen by reference to the drawings. It will thus be seen that I have eliminated the cutting-disks and other attachments commonly employed in machines of this class for severing the wire into sections and have substituted therefor cutting means of simplified 45 and improved construction.

In the operation of my invention the wire a is fed by the feed-rolls p' and s' through the rapidly-revolving arbor B, cutting-plug B', 50 and alining groove c in the shaft C until its end comes in contact with the end of the trip-wire f', lying in the groove in which said wire is advancing. As the trip-wire f' is moved by the advancing feed-wire a the member F and attached lever e are forced outward from the end of the shaft C and the connected clutch mechanism thrown into engagement with the driven pulley I, thus causing a single rotation 55 of the shaft H, disks m and R, and small pinion n, the rotation of said parts being stopped as soon as the terminus of the cam-surface of the disk m has been turned past the roller m' on the lever e, thereby forcing the lever e back to its normal position and releasing the clutch 60 mechanism from engagement with the pulley 65

I. The meshing gears E and n are so proportioned as to adapt a single rotation of the shaft H to cause a rotation of the shaft C equal to the distance between the spaced grooves c therein, thereby causing the portion of the wire a that has been fed into the receiving-groove c to be severed by reason of the cutting edge of said groove revolving past the edge of the plug B' and the next groove c to be moved into alinement with the aperture b' 70 in readiness to receive the advancing wire a. During the rotation of the shaft H the feed of the wire a into the machine is interrupted by reason of the rotation of the cam-disk R, causing the roller t' to travel out of the indented portion R' on the periphery of said disk, thus causing an oscillation of the lever T and arm T' and a lowering of the feed-roll s' from engagement with the driven feed-roll p'. This feature of my invention is most important to a perfect and satisfactory operation of this class of machines, inasmuch as the breaking of the feed simultaneously with the turning movement of the shaft C, which latter necessarily causes a cessation in the advance of the wire until the succeeding receiving-groove has been brought into alining position, prevents the burning off of said wire at its point of contact with said straightener— 80 a fault that very frequently occurs in machines employing a continuous feed—and also prevents the crowding of the end of the wire against the contiguous end of the shaft C during its period of movement. The movement of the parts is so timed and regulated as to cause the pause in the feed to continue only 90 during a single revolution of the shaft H and disk R, the latter being adapted to stop as soon as the roller t', carried by the lever T, has again dropped into the indented portion 100 R', provided in the periphery thereof.

It is obvious that such changes in the form, proportion, and minor details of construction of the parts as fairly fall within the scope of my invention may be made without departing 110 from the spirit or sacrificing any of the advantages thereof.

Having thus described my invention, what I claim as new, and desire to secure by Letters Patent, is—

1. In a wire-working machine, the combination with a wire-receiving shaft, of mechanism for feeding a wire to said shaft, and mechanism adapted to be thrown into operation at a predetermined point in the advance of the wire for intermittently stopping the feed of the wire to said shaft and cause a simultaneous movement of said shaft.

2. In a machine of the class described the combination with a wire-receiving shaft, of a wire-feed mechanism mounted in advance of said shaft and comprising stationary and movably-mounted coacting feed-rolls, means for rotating said rolls, a member adapted when moved to cause a receding movement of said 125

movably-mounted roll to interrupt the feed of the wire to said shaft, and mechanism adapted to cause a requisite movement of said member when the wire has advanced a predetermined 5 distance and a simultaneous movement of said shaft.

3. In a machine of the class described, the combination with a wire-receiving shaft, of a pair of coacting feed-rolls for advancing a wire 10 to said shaft, an oscillatory member adapted when moved to cause a receding movement of said coacting rolls and interrupt the feed of the wire, and mechanism adapted to cause a movement of said oscillatory member when 15 the wire has been advanced to a predetermined distance in said shaft and a simultaneous movement of said shaft.

4. In a machine of the class described, the combination, with a rotatable receiver for the 20 wire having independent wire-receptacles and the bearing-block therefor, of a hardened sleeve rigidly secured on a reduced portion of said receiver adjacent to said block, a hardened-metal plug in said block having an aperture 25 therethrough in alinement with one of the receptacles of said receiver, the said sleeve and plug having their contiguous edges flush and adapted to sever the wire as said receiver is rotated and mechanism actuated by the advancing wire for causing a movement of said 30 shaft to sever the wire when it has been advanced a predetermined distance therein.

5. In a machine of the class described, the combination with means for feeding the wire, 35 of a rotatable shaft having a reduced portion at one end thereof, a hardened-metal sleeve keyed to the reduced portion of said shaft, radially-arranged longitudinal wire-receiving receptacles provided on said shaft and sleeve, 40 a hardened-metal plug longitudinally disposed in flush position to the end of said sleeve and having an aperture therethrough in alinement with said feeding means and a receiving-receptacle in said sleeve, the contiguous edges 45 of said sleeve and plug being formed with cutting edges for severing the wire as said shaft is rotated and mechanism for actuating said cutting parts when the wire has been advanced a predetermined distance in said shaft.

50 6. In a machine of the class described, the combination with means for feeding the wire and a rotatable receiving-shaft, of a hardened-metal plug rigidly mounted in longitudinal alinement with said receiving-shaft and having 55 an opening through which the wire passes to said shaft, a hardened-metal sleeve rigidly secured on said shaft, having a receptacle for the wire and its end flush with said plug for the purpose described and mechanism adapted 60 to be thrown into operation at a predetermined point in the movement of the advancing wire to cause a movement of said cutting parts and a simultaneous cessation of the wire-feed.

65 7. In a machine of the class described, the combination with means for feeding the wire,

of a wire-straightening mechanism, a stationary plug having an opening through which the wire is advanced from said straightener, an intermittently-rotatable receiving-shaft, a hardened-metal sleeve rigid on said shaft flush 70 with said plug and having a series of longitudinal equidistantly-spaced peripheral grooves with cutting edges adjacent to said plug adapted to stand successively in line with the opening therethrough, and means for intermittently rotating said shaft.

8. In a wire-working machine, the combination of a wire-straightening mechanism, oppositely-rotating rolls at one end of and adapted to feed the wire to said mechanism, a wire-receiving shaft mounted at the other end of said mechanism and having one or more peripheral grooves adapted to stand successively in line with the advancing wire, wire-cutting means in advance of said shaft, and means for intermittently interrupting the feed of the wire and causing a simultaneous movement of said shaft when the wire has advanced a predetermined distance.

9. In a machine of the class described, the combination with a rotatable shaft having one or more radially-disposed longitudinal wire-receiving grooves therein, and oppositely-rotating rolls for feeding the wire to said shaft, of a driving-shaft, a loose pulley thereon 90 adapted to rotate said rolls, a clutch mechanism associated with said shaft, connection between said driving-shaft and 100 its adapted when moved to interrupt the feed of the wire, and means adapted to be operated by the advancing wire to trip said clutch mechanism and cause an intermittent rotation of said driving-shaft and a simultaneous movement of said receiving-shaft and interruption of said feed.

10. In a machine of the class described, the combination with a rotatable wire-receiving shaft, and oppositely-rotating shafts carrying a pair of rolls for feeding the wire to said shaft, one of said feed-shafts having movable bearings, of a drive-shaft, a loose pulley 105 thereon, a clutch mechanism for engaging said pulley and causing a rotation of said shaft, a cam-disk keyed to said drive-shaft, a lever adapted to be moved by a rotation of said disk and interrupt the feed of said rolls, gear connection between said receiving and drive shafts, and means adapted to be tripped at a predetermined point in the advance of the wire for throwing said clutch mechanism into operation and causing a simultaneous rotation 115 of said receiving-shaft and interruption of said feed.

11. In a machine of the class described, the combination with the wire receiving and driving shafts and gear connection between said shafts, of a lever extending transversely of the end of said receiving-shaft, a member movable with said lever, means disposed in the path of the wire and secured to said member adapted to be intermittently engaged at 125 130

a predetermined point in the advance of the wire and cause a movement of said lever, means for causing a rotation of said driving-shaft when said lever is moved, and means for stopping said shaft at a predetermined point in its rotation.

12. In a machine of the class described, the combination with a wire-straightening mechanism, of oppositely-rotating rolls mounted at one end of and adapted to feed the wire to said mechanism a wire-receiving shaft at the other end of said mechanism and having a series of longitudinal grooves adapted to stand successively in line with the advancing wire, wire-cutting means in advance of said shaft, and means actuated by the advancing wire for intermittently moving the receiving-shaft to cause the wire to be severed and successively enter the several grooves therein and to cause a simultaneous interruption of the feed thereof.

13. In a machine of the class described, the combination with the wire-straightening mechanism of a stationary hardened-metal plug in axial alignment with said mechanism and having an opening for the passage of the wire therethrough, a rotatable receiving-shaft in advance of said plug and having a series of radially-disposed longitudinal wire-receiving receptacles therein, a hardened-metal sleeve on said shaft having its peripheral surface provided with receptacles to form a continuation of the receptacles in said shaft, the said receptacles being formed with cutting edges flush with said plug and adapted to successively align with the opening therethrough when said shaft is rotated, and means adapted to be tripped by the advancing wire for intermittently rotating said shaft to sever the advancing wire and move the several receptacles successively in alignment with the advancing wire.

14. In a machine of the class described, the combination with an intermittent wire-feed mechanism, of a rotatable shaft having a longitudinally-disposed wire-receiving receptacle therein, means for severing said wire into predetermined lengths, and mechanism for causing an intermittent rotation of said shaft a predetermined distance and a simultaneous interruption of the feed of the wire to said shaft.

15. In a machine of the class described, the combination with an intermittent wire-feed mechanism of a rotatable shaft having a series of longitudinally-disposed wire-receiving grooves therein, means in advance of said shaft for cutting the wire into predetermined lengths, and mechanism adapted to be thrown into operation by the advancing wire for moving said shaft intermittently to cause the wire to successively enter said grooves and be cut into sections and for causing a simultaneous cessation of the feed of the wire during such intermittent movements of said shaft.

16. In a machine of the class described, the combination with a wire-feed mechanism, of a wire-receiving shaft, wire-cutting mechanism associated with said shaft, and mechanism actuated by the advancing wire for intermittently stopping the feed of the wire to said shaft.

17. In a machine of the class described, the combination with a wire-feed mechanism comprising oppositely-rotating shafts, having stationary and movable bearings and a pair of normally contacting rolls on said shafts, of a wire-receiving shaft, means for severing the wire at the limit of its movement into said shaft, and means actuated by the advancing wire for intermittently breaking the contact of said rolls and interrupting the feed of the wire to said shaft.

18. In a machine of the class described, the combination with the wire feed and straightening mechanism, of a rotatable shaft having a series of radially-disposed longitudinal wire-receiving receptacles therein, means for severing the wire as it is advanced into a receptacle, a driving-shaft, gear connection between said receiving and driving shafts, a loose belt-pulley on said latter shaft, a clutch mechanism associated with said pulley and shaft, means actuated by the advancing wire for intermittently throwing said clutch into operation and causing a limited rotation of said receiving and driving shafts, and mechanism actuated by a rotation of said driving-shaft for causing a cessation of the wire-feed during such rotation.

19. In a machine of the class described, an intermittent wire-feed mechanism comprising oppositely-rotating shafts, a pair of rolls carried by said shafts between which the wire is normally gripped, stationary bearings for one and movable bearings for the other of said shafts, means for normally retaining said rolls in contact, a driving-shaft, means on said shaft for continuously driving the shaft having stationary bearings, a cam-disk carried by said driving-shaft, a lever connecting said disk and movable bearings, and means for intermittently rotating said driving-shaft for causing a movement of said movable bearings and interruption of the feed of the wire.

20. In a machine of the class described, the combination of a wire-feed mechanism, a rotatable wire-receiving shaft, means for intermittently rotating said shaft to discharge a wire fed thereto, a wire-cutting mechanism in advance of said shaft, and mechanism adapted to be thrown into operation at a predetermined point in the advance of the wire for causing an interruption of the feed thereof.

In testimony whereof I have hereunto signed my name to this specification this 16th day of February, 1904.

VERNON HOXIE.
